DESIGN FOR A COCKPIT CANOPY OR SIMILAR ARTICLE

Earl O. Weining, Wichita, Kans., assignor to Boeing Airplane Company, Wichita, Kans., a corporation of Delaware

Application March 23, 1945, Serial No. 118,652

Term of patent 14 years

(Cl. D71—1)

To all whom it may concern:

Be it known that I, Earl O. Weining, a citizen of the United States, residing at Wichita, in the county of Sedgwick and State of Kansas, have invented a new, original, and ornamental Design for a Cockpit Canopy or Similar Article, of which the following is a specification, reference being had to the accompanying drawing, forming a part thereof.

Figure 1 is a top plan view of a cockpit canopy
embodying the new design.

canopy.

canopy.

of the same canopy.

I claim:

The ornamental design for a cockpit canopy or similar article, substantially as shown.

EARL O. WEINING,
